5 Claims. (Cl. 254—187)

ABSTRACT OF THE DISCLOSURE

A winch having a rotary axis and a winch drum rotated by said rotary axis through the intermediary of a clutch, a hydraulic cylinder for operating said clutch device, first and second hydraulic systems for operating the hoist motor and the hydraulic cylinder respectively, characterized in that the oil pressure set in the second hydraulic system including said hydraulic cylinder is raised in synchronism with the rotation of the hydraulic motor, and the clutch device is engaged automatically when the hydraulic motor is rotated by a change-over valve installed in said first hydraulic system.

This invention relates to a winch, and more particularly, to a winch having novel driving means.

Heretofore, in the winch of the kind in which the torque of the rotary axis rotated by means of a hydraulic motor is adapted to be transmitted via a clutch to a winch drum, rotation of the winch drum in the one direction or in the other direction was generally effected by rotating a hydraulic motor in the one or hoisting direction or in the other or hoisting down direction and consequently said rotary axis in the desired direction, through operation of a hydraulic change-over valve installed in the hydraulic system including said hydraulic motor, and also by operating a clutch separately from the operation of the hydraulic change-over valve. However, such a winch of the conventional type was beset with difficulties such as unnecessary detrition of the clutch since the operation of the hydraulic motor was not associated operatively with the operation of the clutch and the operation of the clutch was not necessarily carried out while the hydraulic motor remained stationary.

Hence, it is an object of the present invention to provide a winch having a rotary axis and a winch drum rotated by said rotary axis through the intermediary of a clutch and so constructed that the hydraulic system for driving said hydraulic motor may be operated in synchronism with the operation of the hydraulic system including the clutch operating mechanism, and the clutch may be operated automatically and in association with the driving of the hydraulic motor by operating a hydraulic change-over valve installed in the hydraulic system for driving said hydraulic motor.

Other objects of the present invention will become apparent from the following description made in conjunction with the accompanying drawings showing preferred embodiments of the winch of the present invention.

In the drawings:

FIG. 1 is an illustrative view showing another embodiment of a winch including a rotary axis rotated by means of a hydraulic motor and a winch drum rotated by said rotary axis through a clutch device, and also showing a hydraulic system for operating said rotary axis and said clutch device;

FIG. 2 is an illustrative view showing another embodiment of the hydraulic system shown in FIG. 1; and

2

FIG. 3 is a view similar to FIG. 2 and showing illustratively still another embodiment of the hydraulic system.

Referring to the accompanying drawings, especially to FIG. 1, a winch member 1 has a winch drum 2, the outside wall of which is engageable with a brake band 3 encircling it and the inside wall of which is engageable by a pair of clutch shoes 4, 4' provided inside said winch drum. Said pair of clutch shoes 4, 4' being pivoted at their ends 6, 7 to a link 5 are thus coupled together, and the other end of the clutch shoe 4' is coupled by means of a coupling pin 13 to one end of a double-arm lever 11 pivoted by means of a pivot 10 to a plate 9 secured to a rotary axis 8 mounted inside the winch drum 2. Clutch shoe 4 is pivoted at 12 and the clutch shoes 4, 4' are pulled normally radially inwardly of the winch drum 2 by means of springs 26. The free end of the double-arm lever 11 faces to the foremost end of a piston rod 15 of a hydraulic cylinder 14 secured to said plate 9. Pressure oil for operating the clutch may be delivered at any time to the hydraulic cylinder 14 via a pressure oil supply circuit 16 installed through said rotary axis 8. When pressure oil is supplied into the hydraulic cylinder 14 via this circuit 16, piston rod 15 is extended to press against the free end of the double-arm lever 11, which is then turned about pivot 12 to engage the clutch with the clutch shoes 4, 4' displaced outwardly against the force of the spring 26. In this way, the rotary axis 8 and the winch drum 1 are operated cooperatively.

Rotary axis 8 is driven by means of a hydraulic motor 17 via a suitable power transmission device. The construction of a pressure oil supply circuit to the hydraulic motor 17 as illustrated in the drawings comprises a pressure oil pump 18, an oil reservoir 19, a center by-pass type two-way hydraulic change-over valve 20, and a counterbalance valve 21 installed in a pipe 22 for supplying pressure oil in the one or hoisting direction from the reservoir and intermediate the hydraulic motor 17 and the hydraulic change-over valve 20. Reference number 25 indicates a pipe for supplying pressure oil to the hydraulic motor 17 in the other or hoisting down direction. Said counterbalance valve 20 is an outside pilot type in which the oil pressure in the pipe 25 is utilized as a pilot pressure thereof. Pressure oil supply circuit 16 to the hydraulic cylinder 14 is connected, via a hydraulic change-over valve 23, to a part 22a of the pressure oil supply circuit 22 intermediate the hydraulic motor 17 and the counterbalance valve 21, and is adapted to be communicated selectively with the pressure oil supply circuit 22a or with the oil reservoir 19 by changeover of the hydraulic change-over valve 23 installed therein. In the drawings, 24 indicates a check valve installed to prevent pressure fluctuations in the pressure oil supply circuit 16 due to chatter of the check valve 21 which may take place when the direction of rotation of hydraulic motor 17 is reversed. It is not always necessary to install this check valve 24, however, where the counterbalance valve 21 is not liable to chatter.

With the above-mentioned construction of the winch driving means according to the present invention, if the hydraulic change-over valve 20 is moved from the neutral position in the direction indicated by the arrow a, with the hydraulic change-over valve 23 in the position illustrated in the figure, and the hydraulic motor 17 is rotated in the hoisting direction, oil pressure inside the pressure oil supply circuit 22a is raised slightly first of all as a result of resistance encountered at the start of operation of the hydraulic motor 17. Thus, the hydraulic cylinder 14 connected to this circuit 22a is set into motion to engage the clutch automatically and to start the winch drum 2 in the hoisting direction. When the winch drum 2 is started in this direction, oil pressure inside said cir-

cuits 22a and 16 is still raised, so that the clutch keeps on to be engaged and the winch drum 2 keeps on to be rotated in the hoisting direction as long as the hydraulic change-over valve 20 is maintained in the above-mentioned position. When the hydraulic change-over valve 20 is then returned to the neutral position, rotation of hydraulic motor 17 and the rotary axis 8 comes to a stop, but the clutch still keeps on to be engaged. When the hydraulic circuit 16 is communicated with the oil reservoir 19, by operation of the change-over valve 23, oil will flow into the oil reservoir to disengage the clutch and the winch will fall by its own gravity unless the brake 3 is applied.

If the hydraulic change-over valve 20 is operated in the direction indicated by the arrow a', with the hydraulic change-over valve 23 in the position illustrated in the figure, counterbalance valve 21 is not opened and the oil circuit through it is not opened so long as the oil pressure inside the oil pipe 25 is raised until a predetermined value is reached, consequently, hydraulic motor 17 cannot start so long as the pressure oil circuits 22 and 22b are not interconnected. However, when the oil pressure inside the oil pipe 25 is raised, and the hydraulic motor 17 is capable of starting, hydraulic cylinder 14 connected to said circuit 22a at 16 is also operated and the clutch is engaged automatically as in the case of rotation of hydraulic motor in the hoisting direction explained in the foregoing. Thereafter, the clutch keeps on to be engaged and the winch drum 2 keeps on to be rotated in the hoisting down direction as long as the hydraulic change-over valve 20 is maintained in the above-mentioned position.

As above described, according to the winch driving means of the present invention, when the hydraulic motor 17 is driven in the hoisting direction or hoisting down direction by operation of the hydraulic change-over valve 20, clutch is engaged automatically at the same time with or shortly before rotation of the hydraulic motor 17, and the winch drum may be operated in a simple manner in the hoisting or in the hoisting down direction. Since the clutch is engaged at all times when the hydraulic motor is stationary, and the latter is started after the clutch is engaged, detrition of the clutch may be minimized. Moreover, the clutch is operated at all times under constant pressure, the juncture of time at which it comes into play and its working pressure remain constant, and long life of the clutch may be ensured.

The hydraulic system illustrated in FIG. 2 is a modification of that illustrated in FIG. 1, and the corresponding parts are designated by the same reference numerals.

In this modification, pressure oil supply circuit 16 to the hydraulic cylinder 14 is communicated with the pipe 22b intermediate the hydraulic change-over valve 20 and the hydraulic pump 18 via hydraulic change-over valve 23 and check valve 24. The operation of the hydraulic motor 17 and the hydraulic cylinder 14 is same as that described with reference to the winch according to the present invention as shown in FIG. 1.

The hydraulic system illustrated in FIG. 3 is a modification of that illustrated in FIG. 2, especially of the pressure oil supply circuit 16, and corresponding parts are designated by the same reference marks as in FIGS. 1 and 2. In this modification, a throttle valve 25 is installed in the pressure oil supply circuit 16, and a normally closed change-over valve 23 is installed in a circuit branched from said circuit 16 and communicated with oil reservoir 19.

While in the embodiments described in the above with reference to the accompanying drawings an outside pilot

type counterbalance valve, pilot pressure of which is taken from the pipe 25, is used, an inside pilot type counterbalance valve, pilot pressure of which is the oil pressure in the pipe 22, can equally be utilized.

5 What is claimed is:

1. A winch comprising a rotary axis rotated by a hydraulic motor, a winch drum driven by said rotary axis through the intermediary of a clutch device, a hydraulic cylinder for operating said clutch device, a first pressure oil circuit connecting said hydraulic motor and an oil tank and including pipes for supplying pressure oil in the one or hoisting direction and in the other or hoisting down direction, a first change-over valve installed in said pressure oil circuit and operative to stop the flow of oil through said hydraulic circuit and to regulate the oil so as to flow through said hydraulic circuit in the one or hoisting direction and in the other or hoisting down direction, a hydraulic pump provided in the hydraulic circuit from the reservoir intermediate said change-over valve and oil reservoir, a counterbalance valve installed in the pipe for feeding oil in the hoisting direction and intermediate said hydraulic motor and change-over valve, a second pressure oil supply circuit communicating at its one end with said hydraulic cylinder and at the other end with said pipe for feeding oil in the hoisting direction and including said hydraulic cylinder and a second change-over valve arranged to selectively return the oil through it to the oil reservoir; characterized in that the oil pressure set in the secondly-mentioned hydraulic circuit including said hydraulic cylinder is raised in synchronism with rotation of the hydraulic motor and the clutch device is engaged automatically when the hydraulic motor is rotated in the one or hoisting direction or in the other or hoisting down direction by operation of said 35 first change-over valve.
2. A winch as claimed in claim 1 wherein the pressure circuit including the hydraulic cylinder is communicated at one end with said hydraulic cylinder and at the other end with the hydraulic circuit from the reservoir connecting the hydraulic motor and the oil reservoir and intermediate the hydraulic motor and the counterbalance valve.
3. A winch as claimed in claim 1 wherein the pressure circuit including the hydraulic cylinder is communicated at one end with said hydraulic cylinder and at the other end with the hydraulic circuit from the reservoir connecting the hydraulic motor and the oil reservoir and intermediate the first change-over valve and the hydraulic pump.
4. A winch as claimed in claim 1 wherein the pressure oil circuit including the hydraulic cylinder comprises a check valve arranged to feed oil exclusively towards the hydraulic cylinder.
5. A winch as claimed in claim 1 wherein said clutch device includes clutch shoes pivotally mounted on the rotary axis and facing the internal wall of the winch drum, and a lever connected at one end with one of said clutch shoes and mounted engageably with the piston rod of the hydraulic cylinder at the other end.
